William Stark, New York, N. Y., assignor to Aileen Mills
Company, Biscoe, N. C., a corporation of Delaware

Application September 10, 1957, Serial No. 47,683

Term of patent 14 years

(Cl. D92—1)

Fig. 1

My design comprises a series of vertically disposed, uniformly spaced light and dark stripes of uniform width separated by a single tinsel strand, each light colored stripe bearing uniformly disposed self colored chenille tufts within its margins, all as shown.

I claim:

The ornamental design for a chenille textile fabric or similar article, substantially as shown and described.
